UNITED STATES PATENT OFFICE

171,872

CLOTHING HANGER

Charles F. Waldron and Lyle T. Lorenzen,
Phoenix, Ariz.

Application October 30, 1953, Serial No. 27,402

Term of patent 14 years

(Cl. D80—8)

To all whom it may concern:

Be it known that we, Charles F. Waldron, a citizen of the United States, residing at 314 North First Avenue, city of Phoenix, State of Arizona, and Lyle T. Lorenzen, a citizen of the United States, residing at 314 North First Avenue, city of Phoenix, State of Arizona, have invented a new, original, and ornamental Design for a Clothing Hanger, of which the following is a specification, reference being had to the accompanying drawing, forming a part hereof.

Figure 1 is a plan view of a clothing hanger showing our new design;

Figure 2 is a front elevational view of one side thereof;

Figure 3 is an elevational view of the left end thereof;

Figure 4 is an elevational view of the right end thereof; and

Figure 5 is an elevational view of the back side thereof.

We claim:

The ornamental design for a clothing hanger, as shown.

CHARLES F. WALDRON.
LYLE T. LORENSEN.
